UNITED STATES PATENT OFFICE.

HOMER C. STARKEY, OF ENID, OKLAHOMA, ASSIGNOR OF ONE-FOURTH TO JAMES A. JONES, OF OKLAHOMA, OKLAHOMA.

TROUSERS-SUPPORT.

1,285,828.

Specification of Letters Patent. Patented Nov. 26, 1918.

Application filed December 6, 1917. Serial No. 205,827.

To all whom it may concern:

Be it known that I, HOMER C. STARKEY, a citizen of the United States, residing at Enid, in the county of Garfield and State 5 of Oklahoma, have invented certain new and useful Improvements in Trouzers-Supports, of which the following is a specification.

This invention relates to a trousers support and has for its object the production 10 of a simple and efficient support which will snugly fit around the waist of the wearer and by engaging the waist of the trousers, will efficiently support the trousers without permitting the same to sag.

15 Another object of this invention is the production of a simple and efficient means for facilitating the connection of the trousers support, or waist band, with the trousers.

20 With these and other objects in view this invention consists of certain novel constructions, combinations and arrangements of parts as will be hereinafter fully described and claimed.

25 In the drawings:—

Figure 1 is a front elevation of the trousers support,

Fig. 2 is a rear elevation thereof,

Fig. 3 is a section taken on line 3—3 of

30 Fig. 1,

Fig. 4 is a vertical section through the trousers support, showing the same connected to the trousers.

By referring to the drawings, it will be 35 seen that 1 designates the body of the trousers support which is preferably formed from a piece of fabric such as canvas or suitable fabric possessing the desired strength having the sufficient flexible nature 40 to conform to the shape of the body, of the wearer.

The body 1 of the trousers support is provided with seams 2 along its respective edges and one end of the body 1 is provided 45 with a substantially broad flap 3, the opposite end of the body 1 being provided with a comparatively narrow flap 4.

A pair of securing plates 5 are secured to the outer face of the body, near one end 50 thereof, and spring clips 6 are secured to the opposite end of the body 1 and are mounted upon the substantially broad flap 3. A clip 7 is also carried near the front end of the body 1 and extends vertically of the body 55 as shown in Fig. 1, the spring clips 6 ex-

tending longitudinally of the body 1. A plurality of plates 8 are also secured to the outer face of the body 1 and are arranged in staggered relation adjacent the respective upper and lower edges of the body 1. Suitable spring clips similar to the clips 6 and 7 may be carried by the waist band of a pair of trousers or other garment for the purpose of engaging the plates 8 and holding the plates in engagement with the spring clips 65 carried by the trousers.

Each of the plates 5 and 8 comprises a body portion having overlapping side edges 9, the body portions of the plates 8 being provided with suitable securing apertures 10 70 for the purpose of permitting the plates 5 and 8 to be stitched or otherwise secured to the body 1.

Each of the spring clips 6 and 7 is provided with an inner securing eye 11 and a 75 pair of side securing eyes 12, these securing eyes 11 and 12 being adapted to be stitched or otherwise secured to the support such as the body 1 or a pair of trousers which are adapted to be supported in engagement with 80 the body 1. The outer ends 13 of the spring clips 6 and 7 are free to spring inwardly and outwardly and are provided with laterally bent hook portions 14 which hook portions are adapted to overhang the ends of 85 the plates 5 and 8. The overlapping side edges 9 constitute overhanging lips or flanges which are spaced from each other along their edges to permit the outer ends 13 of the spring clips 6 and 7 to pass there- 90 between and fit under the same, in this manner firmly holding the clips 6 and 7 in engagement with the plates 5 and 8.

From the foregoing description it will be seen that a very simple and efficient means 95 has been produced for supporting a pair of trousers neatly around the waist of a wearer, and at the same time preventing the trousers binding around the waist of the wearer. By means of the present device, the use of 100 a belt and suspenders may be done away with for the reason that the supporter will detachably engage the inner waist line of the trousers and neatly support the same in a proper position.

The flexible body 1 is of considerable width, and in view of the broad nature of the body, the same will firmly fit around the waist or hips of the wearer for comfortably supporting a garment. The flexi- 105 110

ble body 1 may be placed over the tails of a shirt and in this way prevent the same from riding up over the top of the garment supported thereby.

- 5 A securing plate 8' is carried by the garment 1^a for the purpose of engaging the vertically extending spring clip 7.

What is claimed is:—

- As a new article of manufacture a trousers 10 supporter comprising a comparatively broad flat band, adapted to fit upon the inner face of the waist band of the garment, a plurality of sheet metal clip receiving sockets secured to the outer face of said band and arranged 15 in staggered relation along the edges of said band, said clip receiving sockets provided

with rolled edges adapted to receive spring clips carried by a pair of trousers, spring clips secured near one end of said band, sockets carried near the opposite end of said band and adapted to receive said last mentioned clips, and said clips provided with parallel spring portions having overhanging ends adapted to overhang the edges of the coöperating sockets.

In testimony whereof I affix my signature in presence of two witnesses.

HOMER C. STARKEY.
